PATENTED
OCT 15 1867

Design No. 2,800
D. A. Rogers, Design, for

Design No. 2,800

United States Patent Office.

THEODORE A. DORGAN, OF BALTIMORE, MARYLAND.

Design No. 2,800, dated October 15, 1867.

DESIGN FOR A STOVE-DOOR.

The Schedule referred to in these Letters Patent and making part of the same.

TO ALL WHOM IT MAY CONCERN:

Be it known that I, THEODORE A. DORGAN, of Baltimore, in the county of Baltimore, and State of Maryland, have invented or produced a new and original Design for the Fire-Doors and Windows of a Stove, of which the following is a full, clear, and exact description, reference being had to the accompanying drawing, making part of this description or specification.

The stove-doors and windows to which this design is applicable, are those provided with perforated plates and backed by mica or other transparent material, so as to show ornamental figures by the light of the fire within the fire-chamber.

Referring to the drawing, A B is the fire-door of a stove, hinged to the usual frame C D, and E E a series of perforations, in the form of letters, arranged to indicate words.

What I claim as my invention, and desire to secure by Letters Patent, is—

The design for the fire-doors and windows of a stove, herein set forth and shown.

T. A. DORGAN.
